ATTORNEY

UNITED STATES PATENT OFFICE.

DANIEL WEBSTER CLEGG, OF STAPLETON, NEW YORK.

LIGHTING AND HEATING APPARATUS.

SPECIFICATION forming part of Letters Patent No. 485,827, dated November 8, 1892.

Application filed August 14, 1889. Renewed April 30, 1892. Serial No. 431,365. (No model.)

To all whom it may concern:

Be it known that I, DANIEL WEBSTER CLEGG, of Stapleton, in the county of Richmond and State of New York, have invented 5 certain new and useful Improvements in Lighting and Heating Apparatus; and I do hereby declare that the following is a full, clear, and exact description of the invention, which will enable others skilled in the art to 10 which it appertains to make and use the same.

The object of this invention is to provide a simple, cheap, and effective apparatus whereby culinary and other operations requiring 15 heat may be performed without necessarily using the light accompanying the flame from which the heat is derived. Said invention comprises certain novel combinations of parts whereby said objects are effectually 20 secured.

Figure 1 is a side elevation and partial sectional view illustrating the said invention. Fig. 2 is a horizontal sectional view taken in the line $\alpha\alpha$ of Fig. 1.

25 A represents a chimney, which may be that of an ordinary kerosene-lamp with any suitable burner. When it is desired to utilize the light from the latter, this chimney should be of glass. When it is not specially desired 30 to utilize the light aforesaid, said chimney may be of metal or other opaque material. In practice it is preferred to employ a kerosene-lamp having any suitable burner.

The part shown at B in the drawings indicates the oil-reservoir of a kerosene-lamp, of 35 which a is the circumferential rim or burner, the chimney A being supported thereon in the usual or any suitable manner.

C indicates the cone of a burner; but an 40 Argand or any other suitable kind of burner may be employed.

F is a shell made, preferably, of metal and conforming in its general outline to the adjacent portion of the chimney A, with a space 45 b between it and the chimney. Any desired number of holes or orifices c are formed in said shell.

d are annular plates, the central openings of which correspond in shape and size 50 with the adjacent portion of the chimney A, so that the said chimney, being thrust into said openings, the shell F is supported there-

on, as shown in the drawings. In the annular plates d are any desired number of holes or orifices a' . The shell F, being capable of attachment to a chimney A, as just described, is when so attached the means whereby the other operative parts of the apparatus are supported, as hereinafter presently explained.

55 G is a shade intended to be capable of serving the double purpose of an ordinary lampshade and of a deflector, by which external atmospheric air may be gathered and deflected upward to the opening b' at the top of 60 said shade. This shade is attached to or carried by the shell F, as hereinafter described. Placed upon or attached to the shade G is a cylinder H, which is substantially concentric with the shell F, and consequently with the 65 upper part of the chimney A. Said cylinder being of greater diameter than the shell F, provides a chamber f around and above the shell F. Placed upon the cylinder H are one or more plates I. When desired, said plate 70 or plates may be imperforate; but for certain uses they should be provided with numerous holes or openings. By placing one perforated plate over another, but without especial care that the perforations in one will coincide with 75 those in the other, a more diffused passage of the hot air and gaseous products of combustion through said plate or plates will be secured. As the equivalent of a perforated plate or plates I one or more sheets of wire- 80 gauze may be employed.

85 The operation of the apparatus is as follows: The heat of the flame from the burner C causes in the usual manner the ascension within the chimney A of the hot products 90 of combustion mingled with a relatively-large volume of highly-heated air supplied to and around the burner in the usual manner. Simultaneous with this a volume of air less heated is carried upward through the 95 chamber b and above the chimney A mingles with the heated aeriformed products issuing from said chimney, the whole passing into the chamber f . From the chamber f , when the plates I are perforated, a portion of the highly- 100 heated products passes through said plate I, the remainder passing outward radially from the top of the shell F and thence downward through the space between the sides of the

shell F and the cylinder H, finally making their escape through the openings b'' , with the exception of whatever portion may pass through the openings a' into the space b between the chimney and the shell F, which latter portion passes up and again joins the ascending current in the chimney A. By the means aforesaid a large volume of air heated to the requisite degree continually fills the chamber f and heats the plate I above it, and when said plate I is foraminated it permits a series of thin diffused streams of hot air and products of combustion to pass upward and outward.

In the meantime the lateral surface of the cylinder H affords means for the effective radiation of heat in the apparatus. Any suitable cooking utensil may be placed upon the plate or plates I, or in lieu thereof any suitable article to be broiled, toasted, or the like may be laid upon said plate or supported above the same by any suitable means.

When the chimney is made of glass, all the light usually utilized is made available without interfering with the utilization of the heat which accompanies the production of said light. When it is not desired to utilize the light, the chimney may be made of metal or some material less frangible than glass. In such case it is not necessary that a reflecting-surface be given to what is designated as the

"shade" G. A deflecting-plate K may be interposed between the top of the shell F and the plate I above at such distance from the former as to permit the hot-air products of combustion, &c., to pass out into the chamber f , as described, the office of said deflecting-plate K being to more effectually distribute the hot-air, products of combustion, &c., equally around the upper part of the chamber f . When de-

sired, the lowermost of the plates I may be formed integral with the cylinder H, as shown in the drawings. The annular plates d may, when desired, be made of wire-gauze, or, if preferred, may be formed of series of inwardly-extending projections to the shell F, it being sufficient that the parts be of such character as to sustain the shell F in proper relation with the chimney and with the space b between said shell and the chimney.

50. What I claim as my invention is—

1. The combination, with a chimney A, of a shell F, constructed to be suspended from the chimney and concentric therewith and to provide a space b between itself and said chim-

ney, the deflecting-shade G, carried by said shell, a cylinder H, arranged around said shell with a chamber f between, and a plate placed above the shell and chimney, all substantially as and for the purpose herein set forth.

2. The combination, with a chimney A, of a shell F, arranged around said chimney with a space b between, a shade G, attached to said shell, a cylinder H, placed around said shell with a chamber f between, and a foraminated plate I, placed above the shell and chimney, substantially as and for the purpose herein set forth.

3. The combination, with a chimney A, of a shell F, provided with perforations a' and arranged around said chimney with a space b between, a shade G, attached to said shell, a cylinder H, placed around said shell with a chamber f between, and a plate I, placed above the shell and chimney, substantially as and for the purpose herein set forth.

4. The combination, with a chimney A, of a shell F, provided with perforations a' and arranged around said chimney with a space b between, a shade G, attached to said shell, a cylinder H, placed around said shell with a chamber f between, and a foraminated plate I, placed above the shell and chimney, substantially as and for the purpose herein set forth.

5. The combination, with a chimney A, of a shell F, arranged around said chimney with a space b between, a shade G, attached to said shell, a cylinder H, placed around said shell with a chamber f between, a plate I, placed above the shell and chimney, and a deflecting-plate K, interposed between the top of the shell F and the plate I, substantially as and for the purpose herein set forth.

6. The combination, with a chimney A, of a shell F, provided with perforations a' and arranged around said chimney with a space b between, a shade G, attached to said shell, a cylinder H, placed around said shell with a chamber f between, a foraminated plate I, placed above the shell and chimney, and a deflecting-plate K, interposed between the top of the shell F and the plate I, substantially as and for the purpose herein set forth.
